UNITED STATES PATENT OFFICE

CHARLES F. A. HINRICHES, OF BROOKLYN, NEW YORK.

DESIGN FOR HANDLES OF CHINA AND OTHER VITRIFIED WARE.

Specification forming part of Design No. **11,483**, dated November 4, 1879; application filed October 6, 1879.
[Term of patent 7 years.]

To all whom it may concern:

Be it known that I, CHARLES F. A. HINRICHES, of Brooklyn, in the county of Kings and State of New York, have invented or produced a Design for the Handles of China and other Vitrified Ware, of which the following is a specification.

This design is adapted to the handles of dishes, dish-covers, bowls, and covers, cups, mugs, pitchers, and other articles made of china, glass, earthenware, or other vitrified substances.

The design of the handle is represented by the side view, Figure 1, and plan, Fig. 2, as applied to a bowl-cover.

The handle is made to represent a loop or coil of cord with a pin or marline-spikes through the same, the ends of the imitation cord being spread at the place of union with the surface of the cover, bowl, or other article upon which it is placed.

The portion *a* represents the marline-spikes

as if passed through the convolutions *b*, that represent a rope or cord, and the ends *c* of such imitation cord are spread, as at *d*, and united to the surface of the bowl-cover or other vitrified article.

The size of this handle will depend upon the size of the article upon which it is placed, and it may be gilded, or partially gilded, or colored on the surface, if desired.

I claim as my invention—

The design of the handle for vitrified substances, consisting of the representation of a coil of rope or cord with marline-spikes or a pin through it, the ends of the coil being at the place of attachment of the handle.

Signed by me this 2d day of October, A. D. 1879.

C. F. A. HINRICHES.
